UNITED STATES PATENT OFFICE.

CHARLES AUGUST JOHNSON, OF CHICAGO, ILLINOIS.

BASKET AND THE LIKE.

1,178,924.

Specification of Letters Patent. Patented Apr. 11, 1916.

Application filed April 19, 1915. Serial No. 22,328.

To all whom it may concern:

Be it known that I, CHARLES AUGUST JOHNSON, a citizen of the United States, residing at 3205 Fullerton avenue, in the city of Chicago, county of Cook, and State of Illinois, have invented a new and useful Basket and the like, of which the following is a full, clear, concise, and exact description, reference being had to the accompanying drawing, forming a part of the specification.

My invention relates to an improved method of basket working, particularly the making of flower baskets and the like and has for its main object the production of baskets of any and all sizes, shapes and styles by the use of a single piece of material for the main body portion of the basket.

In carrying out my new process in the present preferred manner I use for the main body portion a single piece of cardboard of a weight to be determined by the size of the basket to be made although I do not wish to be limited to this material as any suitable material, such as paper of various weight and texture, bark, leather, metal, veneer, reed or the like can be used.

In the accompanying drawing I show the substantial steps in my process making one form of basket,

Figure 1 is a perspective view of the sheet of material from which the body portion is to be made. Fig. 2 is a perspective view of the same sheet slitted. Fig. 3 is a perspective view of the same piece of material with the rib members interwoven into the slits. Fig. 4 is a perspective view showing the body portion being assembled on and with the bottom member. Fig. 5 is a perspective view of the finished basket.

In carrying out my process I first select a sheet of material (Fig. 1) of the proper size to give the height and circumference required for the basket to be made, cut to a shape which will determine the shape of the basket when finished. In practice I prefer to use cardboard for this material because of its cheapness, the ease with which it can be worked in my method and its adaptability to treatment to give it hardness of finish and imperviousness to moisture, although I do not wish to be limited in material as anything of sufficient flexibility can be used. I next take the material and by means of a sharp knife or other instrument and a die or like frame provide the sheet of material

with a plurality of parallel slits (10) as shown in Fig. 2 extending substantially throughout the length of the sheet of material but leaving at each end thereof sufficient uncut portion (11) to form a seam when the two ends of the sheet are brought together either in the shape of a cylinder, cone or whatever shape the basket is to assume.

In carrying out my process I next take a number of ribs or posts (12) as in Fig. 3 of size adapted to the basket being made and of any material sufficient to give the proper strength such as wood, wire, and the like, wood generally being used and weave these ribs into the slits of the sheet at sufficient intervals to give the required strength. I next provide a bottom portion (13) as shown in Fig. 4 which may be of any material but will probably be best made of light weight wood cut to shape and size for the style of basket to be made. In assembling the body portion as it appears in Fig. 3 with the bottom member as shown in Fig. 4 it will be found convenient to place the bottom portion in a vise or suitable grip and tack the posts or ribs to said bottom portion beginning for instance at 14 and continuing around the circumference of the bottom portion. When this step is completed the edges of the sheet (as shown in Fig. 3) will overlap and form a seam (15) as shown in Fig. 5. In order to give additional strength and a finished appearance to the basket I

next provide a hoop or band 16 which may be made of reed or other analogous and suitable material which band or hoop is placed around the outer circumference of the bottom of the basket as shown in Fig. 5, and fastened by tacking or other suitable means. I next provide at the top of the basket additional strengthening and finishing means 17 which in practice may be reed or other suitable strips of sufficient strength, flexibility and suitable appearance. The number of these finishing and strengthening strips will be determined by the size, shape and style of basket being made. The strips will be woven in and out around the tops of the ribs or posts 12. The basket proper is now completed but I next provide a handle (18) of any desired material, size, shape and style desired. It will be found convenient to fasten the handle at the sides to adjacent sides of the basket reaching to the bottom thereof, one side of the handle member over-

lapping the seam 15 for giving additional finish and strength. The bottom portion of the handle may be fastened to the bottom member 13 as shown at 19 in Fig. 5 which 5 will procure additional strength and rigidity and the handle may be additionally fastened to the sides and top of the basket as required to procure the proper strength and appearance. The handle is usually fastened at 10 the top of the basket by means of wire or other loops and the like.

The basket when completed I treat with a coating material, such as shellac, varnish or stain like kerosene and creosote composition stains, to give the material used in the body portion of the basket, particularly if that material be pasteboard or paper, the necessary finish, hardness and moisture resisting properties.

20 The product obtained by the method herein described, being both a new and novel article of manufacture, I also ask protection thereon in the appended claims.

I do not wish to be limited to the precise 25 steps in carrying out my process herein described as variations in details may be found desirable and I have herein sought to explain my new method of making baskets and the like by such steps as will be found 30 satisfactory in use. Neither do I wish to be limited to materials as my process will be found equally satisfactory and effective no matter what the material so long as it 35 has any adaptability for use in the basket making or analogous arts.

Having thus described my invention and the product to be obtained by my new method, what I claim and desire to secure by Letters Patent of the United States is:

1. A basket having a body portion made 40 of a single piece, cut to shape and size and provided with a plurality of slits interwoven with ribs, having a bottom member, a strengthening and finishing hoop or band around the bottom, finishing and strengthening bands interwoven with the ribs at the 45 top and a handle substantially as herein shown and described.

2. A receptacle having a body portion made of a single part cut to shape and size 50 and provided with a plurality of continuous slits into which are interwoven ribs or posts, strengthening and finishing members at the top and bottom, and a bottom portion substantially as shown and described.

3. A basket having a body portion made of a single piece of material cut to size and shape and provided with a plurality of circumferential parallel slits into which are interwoven a plurality of upright posts or 60 ribs, a solid bottom member, a strengthening and finishing band or hoop at the bottom, strengthening and reinforcing circumferential bands at the top interwoven with the tops of the upright posts and a suitable 65 handle substantially as herein shown and described.

In witness whereof, I hereunto subscribe my name to this specification.

CHARLES AUGUST JOHNSON.
